ASSIGNORS TO INGERSOLL-RAND COMPANY, OF JERSEY CITY, NEW JERSEY, A COR-
PORATION OF NEW JERSEY

COMPRESSOR-REGULATING APPARATUS

Application filed March 19, 1928. Serial No. 262,827.

This invention relates to gas compressor regulating apparatus.

One object of the invention is to stabilize the pilot valve of a gas compressor regulator so that unloading of the compressor is accomplished in distinct steps.

A further and more specific object is to prevent the pilot valve of the regulator from fluttering, due to exhaust back pressures created by the operation of the valve.

Other objects and advantages of the invention will be in part obvious and in part pointed out hereinafter.

The drawing shows a vertical section through a regulator and pilot valve constructed in accordance with the practice of the invention. The cylinder and its inlet valves associated with the pilot valve also are shown in horizontal section and on a reduced scale with respect to the pilot valve.

Referring to the drawing, the invention is shown associated with a compressor comprising a cylinder A having a piston B and clearance controlling valves C, D, E and F associated with suitable clearance pockets G, H, J and K respectively. The clearance valves C, D, E and F are adapted to be operated or kept closed by the pressure of motive fluid in suitable chambers L provided with pistons O which press the valves C, D, E and F to their seats. If pressure is relieved in the chambers L, suitable springs P return the pistons O lifting the valves C, D, E and F from their seats thereby increasing the clearance of the cylinder A and unloading the compressor a predetermined amount.

The compressor cylinder A is unloaded in steps depending upon the air consumption of the apparatus connected with the discharge of the compressor and it is therefore desirable that the clearance valves C, D, E and F should be opened successively. In this arrangement the compressor is therefore adapted to be operated at full load, three-quarter load, one-half load, one-quarter load, or no-load, depending upon the position of the valves C, D, E and F as will be understood. As shown in the drawing, the compressor is indicated as operating at three-quarter load, the valve C being shown open so as to increase the clear-

ance of the cylinder by adding the clearance of the chambers G.

The regulating apparatus for operating the valves C, D, E and F include an arm Q pivoted at one end as at R to support S mounted on a suitable base T, the arm Q being weighted at its end U opposite the pivot R and held balanced by means of air pressure from the discharge line (not shown) of the compressor. Such motive fluid under pressure is admitted through a pipe V into a base W fitting within cup X mounted on the base T and such pressure is exerted against a second cup Y within an expandable member Z, such as a sylphon attached to the member W. The second cup Y is provided with a pointed rod b resting in that cup and bearing against the arm Q on a knife edge c.

A pilot valve is provided to control the admission and exhaust of motive fluid or compressed gas from the cylinders L. This pilot valve includes a valve chamber d having a longitudinal bore e provided with longitudinally spaced ports f, g, h and j associated with the clearance control valves C, D, E, and F respectively by means of suitable pipes k, o, p and q respectively. Within the valve chamber bore e, a piston r is adapted to reciprocate to control the exhaust of motive fluid or compressed gas from the chambers L. The admission of such motive fluid into the chambers L is accomplished by the provision of a supply pipe s connected to a port t in the bore e, the piston r being provided with a neck u between its ends so as to permit motive fluid to pass from the port t to one or more of the ports f, g, h and j when the latter ports are not uncovered by the end of the piston r. The lower end of the piston r is relatively narrow as shown at v so as to prevent motive fluid from passing to the lower end of the bore e which is provided with an outlet w and an exhaust pipe x.

The upper end of the piston r is connected by means of a rod y and pivot z to the arm Q so as to reciprocate as the arm Q raises or lowers.

The operation of the apparatus so far described is as follows: When the pressure in the discharge line of the compressor reaches a pre-

determined amount, the arm *Q* is raised by that pressure exerted under the second mentioned cup *Y*. The arm *Q* thereupon raises the piston *r* so that its end *v* uncovers in succession the ports *f*, *g*, *h* and *j* closing such ports to the admission of motive fluid from the port *t* and permitting the exhaust of compressed gas from the chambers *L* associated with the clearance valves *C*, *D*, *E* and *F* respectively. 5
Usually the complete unloading of the compressor is not desirable or necessary since the consumption of the motive fluid compressed by the piston *B* usually continues though not at the full rate. It is therefore desirable that 10 only one of the valves *C*, *D*, *E* and *F* be opened at a time so as to gradually unload the compressor to the required degree. The discharge pressure will lift the arm *Q* sufficiently to uncover the port *f*, thereby accomplishing one- 15 quarter unloading or three-quarter loading at which time the compressor gas is discharged from the port *f* into the exhaust pipe *x*.

If the compressor is indoors or is compressing an unpleasant or noxious gas, it is not desirable to permit the gas to discharge near the compressor and therefore the exhaust pipe *x* is often long causing a considerable back pressure in the bore *e* under the head *v* of the piston *r*. It will be noted that the arm *Q* is delicately balanced by the pressure under the cup *Y* and often therefore the pressure of the exhaust pressure onto the piston *r* causes the piston to rise, sometimes raising it sufficiently far to uncover one or more of the ports *f*, *g*, *h* or *j*. This effect is cumulative since the additional exhaust pressure from the port *g* will send the piston *r* further up and uncover the port *h* and a repetition of this 20 action sends the piston still further up.

This is avoided by the provision of a latch to lock the piston *r* in position after uncovering one of the ports *f*, *g*, *h* or *j*. The latch includes a plunger 2 slidable in a guide 3 and attached at its upper end by a pivot 4 to the arm *Q*. Below the guide 3 in the base *T* is provided a roller 5 to further support the plunger 2. The plunger 2 is provided with notches 6, 7, 8 and 9 corresponding to the positions of the piston *r* with respect to the ports *f*, *g*, *h* and *j* at three-quarter load, one-half load, one-quarter load and no-load respectively. A detent is provided to cooperate with the notches, 6, 7, 8 and 9 so as to prevent slight movements of the arm *Q*. This detent includes an arm 10 mounted on a pivot 11 and provided at its free end with a rotatable square block 12 engaging the notches 6, 7, 8 and 9. The arm 10 is pressed against the plunger 2 by means of a spring 13 held in place in the base *T* by means of a screw 14. The detent is adapted to prevent only the slighter tendencies of the arm *Q* to move.

The arm *Q* is prevented from moving due 65 to exhaust pressure from the ports *f*, *g*, *h* and

j under the piston *r* by means of a second arm 15 which is normally out of engagement with the notches 6, 7, 8 and 9 being held in this position by a coil spring 16 at one end. The spring 16 is held in position by a screw 17 similar to the screw 14. The opposite end of the arm 15 is provided with a pin 18 which is adapted to fit into the square bottoms of the notches 6, 7, 8 and 9 and when in that position, the plunger 2 is rigidly held against movement. It is desirable that movement of the plunger 2 should be prevented only temporarily and only after one of the ports *f*, *g*, *h* and *j* has been uncovered. To this end the arm 15 is operated by the pressure of the exhaust existing in the pipe *x*. Such pressure is transmitted to a cylinder 19 provided with a piston plunger 20 having a piston rod 21 adapted to bear against the arm 15. A pipe 22 connects the cylinder 19 with the exhaust pipe *x*. If desired, the pipe *x* may be smaller as at 23 if it connects with the pipe 22. 75

It will thus be seen that when the exhaust occurs from one of the ports *f*, *g*, *h* and *j* into the lower end of the bore *e*, pressure is transmitted through the pipes *x* and the pipe 22 into the cylinder 19 whereupon the piston 20 is pushed forwardly and its piston rod 21 presses against the arm 15 to cause the pin 18 to engage one of the notches 6, 7, 8 or 9 thereby locking the arm *Q* and the piston *r* rigidly in position after having uncovered one of the ports *f*, *g*, *h* or *j*. When the exhaust pressure has been dissipated through the pipe 23, the spring 16 returns the arm 15 to its normal disengaged position and permits further movement of the arm *Q* and the piston *r* upon corresponding rise of the pressure in the discharge line of the compressor.

Thus by the above construction are accomplished among others the objects hereinbefore referred to.

We claim:

1. A compressor regulating apparatus comprising in combination a pilot valve having a valve chest provided with a plurality of ports and a longitudinally movable piston adapted to control exhaust of air under pressure from said ports to the atmosphere, and pressure actuated means to prevent such exhaust from effecting further movement of said piston.

2. A compressor regulating apparatus comprising a pilot valve having a valve chest provided with a bore and spaced ports in said bore, and a piston longitudinally movable in said bore to control the exhaust of compressed gas from said ports to atmosphere, and means actuated by exhaust pressure to prevent movement of said pilot valve by such exhaust pressure during its passage through the bore.

3. A compressor regulating apparatus comprising a pilot valve having a valve chest provided with a bore and spaced ports in

- said bore, a piston longitudinally movable in said bore to control the exhaust of compressed gas from said ports to atmosphere, and a latch actuated by such exhaust of pressure to lock said piston in place after uncovering one of said ports. 5
4. A compressor regulating apparatus comprising a pilot valve having a valve chest provided with a bore and spaced ports in said bore and a piston longitudinally movable in said bore to control the exhaust of compressed gas from said ports to atmosphere, and a latch temporarily actuated by exhaust pressure to lock said piston in place after uncovering one of said ports. 10
5. A compressor regulating apparatus comprising a pilot valve having a valve chamber with a bore having spaced ports therein, a piston longitudinally movable in said bore to control the exhaust of compressed gas from said ports to atmosphere, a latch adapted to lock said piston against movement after said piston has uncovered one of said ports, and a detent spring actuated to resist movement of said piston. 15
6. A compressor regulating apparatus comprising a pilot valve having a valve chamber with a bore and ports spaced in said bore and a piston longitudinally movable in said bore to control the exhaust of compressed gas from said ports into said bore, a latch operated by the pressure of such exhaust to lock said piston temporarily in position after uncovering one of said ports, and a spring operated detent normally resisting movement of said piston. 20
7. A compressor regulating apparatus comprising a weighted arm pivotally mounted, pressure operated means for moving said arm, a pilot valve operated by said arm having a valve chest provided with ports communicating with unloading valves of the compressor, said ports being longitudinally spaced from each other, a longitudinally movable piston in said valve chest to control the exhaust of compressed gas from said ports and operable by said arm, and a latch operable by the pressure of such exhaust to hold said arm and piston rigidly in position after said piston has uncovered one of said ports. 25
8. A compressor regulating apparatus comprising a pivotally mounted arm, means actuated by the discharge pressure of said compressor for balancing and moving said arm, a pilot valve operable by said arm having a valve chest provided with ports associated with the unloading valves of the compressor, a piston longitudinally movable to uncover said ports successively upon movement of said arm, a plunger movable by said arm provided with notches corresponding to the ports in said valve chest, and a latch arm to engage the notches of said plunger and temporarily operated by the exhaust from said ports when uncovered by the piston to 30
- lock said arm and piston in position until said exhaust is dissipated, and a spring actuated detent cooperating with said notches to resist movement of said plunger. 35
9. A compressor regulating apparatus, comprising a pilot valve having a valve chest provided with a bore, ports in the valve chest opening into the bore at spaced intervals along the length thereof, an atmospheric vent at one end of the bore, a reciprocable piston in the bore to control communication between the ports and the vent, and means actuated by the exhaust pressure flowing from said atmospheric vent to prevent movement of the piston by such exhaust pressure during its passage through the bore. 40
